ROLLING SCREEN

Application filed May 11, 1928. Serial No. 277,044.

This invention relates to a screen of the type which is mounted upon a roller and which is movable longitudinally so as to cover an opening such as a window when desired, or to be moved to an ineffective position wound upon the roller. The edges of such screens commonly are engaged in grooves, and move longitudinally along said grooves when the screen is shifted from one position to another. Such screens frequently become disengaged from their retaining grooves, as by inadvertent pressure thereagainst, the force of the wind or the like, and it is extremely difficult to replace the edges of the screen in the grooves.

The purpose of the present invention is to provide simple and effective means for replacing the screen quickly and easily in its guiding grooves after it has become disengaged therefrom.

Another object of the invention is to provide means for so repositioning the screen which may be attached easily to existing structures without necessitating extensive rebuilding of them.

A further object of the invention is the provision of guiding means which will automatically replace the disengaged edges of a screen in their retaining grooves when the screen is moved longitudinally past the guiding means.

To these and other ends the invention resides in certain improvements and combinations of parts, all as will be hereinafter more fully described, the novel features being pointed out in the claims at the end of the specification.

In the drawings:

Fig. 1 is an elevation of a window and a rolling screen applied thereto, illustrating a preferred embodiment of the invention;

Fig. 2 is a vertical sectional view taken approximately along the center line of Fig. 1;

Fig. 3 is a horizontal sectional view of a part of the screen and the retaining means

and guiding or replacing means therefor, illustrating the screen in normal position;

Fig. 4 is a view similar to Fig. 3 illustrating the screen out of its normal position so that its edge has become disengaged from the groove;

Fig. 5 is a horizontal sectional view somewhat similar to Fig. 4, but taken below the plane of the guiding means, and illustrating the edge of the screen disengaged from the groove;

Fig. 6 is a fragmentary elevation of one of the clamping plates constituting one of the side walls of the groove, showing the application of a guiding member thereto;

Fig. 7 is a fragmentary edge view of a pair of clamping members constituting the side walls of a groove, showing guiding members applied thereto, viewed at right angles to Fig. 6;

Fig. 8 is an elevation of a part of a window with a screen therein, showing guiding members of a modified form;

Fig. 9 is a horizontal section taken approximately on the line 9—9 of Fig. 8;

Fig. 10 is a view similar to Fig. 6 illustrating another modified form of guiding member, and

Fig. 11 is a horizontal sectional view of a pair of clamping plates and guiding members of the form shown in Fig. 10, taken approximately on the line 11—11 of Fig. 10.

Similar reference numerals throughout the several views indicate the same parts.

Referring now especially to the form of invention shown in Figs. 1 to 7 inclusive, it will be seen that there is provided a screen 21 mounted upon a roller 22 within a housing 23 near the top of a window or other opening. A crossbar 24 is attached to the lower end of the screen. The vertical edges of screens such as this are ordinarily retained in grooves extending along the sides of the supporting means or window frame 24a. The side walls of these grooves may be

formed, for example, by clamping plates 25 movably mounted within channels, the walls of which are formed by plates 26, shown especially in Figs. 3, 4 and 5. Normally the edges of the screen 21 extend into the groove between the clamping plates 25 in the manner shown in Fig. 3, and sufficient clearance is allowed between the plates and the screen so that the screen may slide longitudinally in this groove as it is rolled upon or unrolled from the roller 22.

When the screen has been adjusted to its desired position, it may be clamped tightly in place by moving the clamping plates 25 inwardly or toward the left as viewed in Fig. 3, which will result in clamping the plates tightly together and gripping the screen between them. This action takes place on account of the hollow bead 27 formed on the outer edge of each of the clamping plates, which bead comes in contact with the rounded portion 28 at the edge of the channel plates 26, when the clamping plates move to the left, and acts as a cam to force each of the clamping plates toward the other. The mounting of the clamping plates within the channel plates, and the moving of the same to a predetermined position therein either manually or by means not shown produces a gripping action on the screen caused by the cam action afforded by moving the elements 27 on the inclined portions of the elements 28.

Mounted on each of the clamping plates 25 which form the side walls of the screen receiving groove, is a guiding member which extends outwardly in a general direction toward the central portion of the screen. This guiding member may consist of a loop-like element having its ends 30 fixed in the hollow bead 27 of the clamping plates and its mid portion 31 extending outwardly, as shown in Fig. 6, and spaced from the edges of the screen receiving groove. The guiding members are arranged near the top of the grooves a short distance below the roller, as shown in Figs. 1 and 2. It will be noted from Figs. 3, 4 and 7 that the guiding members are placed obliquely so that they diverge slightly from the normal plane of the screen although they extend in a general direction toward the opposite groove on the other side of the window.

The use of the device is exceedingly simple and obviates the necessity of taking apart the walls of the screen-receiving grooves in order to replace a disengaged screen, as has frequently been necessary heretofore. It sometimes happens that a sudden gust of wind will blow the edges of the screen out of its grooves, before the screen has been clamped tightly between the clamping plates 25. Such a screen disengaged from the grooves is shown in Figs. 2, 4 and 5. It will be noted that the guiding members 31 extend out sufficiently far from the grooves so that the

edges of the screen are retained between them at all times, and there is very little likelihood of the screen pulling out from between these guiding members, especially since these members are placed comparatively close to the top of the window opening. One edge of the screen at the elevation of the guiding members will then appear as in Fig. 4, while at an elevation slightly below the guiding members the edge of the screen will be in the relation to the groove shown in Fig. 5.

Now if the screen be raised so that it is rolled up on its roller 22, each portion of the edge of the screen, as it reaches a position between the guiding members 31, will be guided or forced into the plane of the grooves, and will thus be free to spring back or become seated in its normal position in the grooves. In other words, all that is necessary to replace a disengaged screen is to raise it so that the disengaged edges thereof pass the guiding members, and the screen will be replaced automatically. The screen may then be lowered again if desired and it would be found to be properly seated in its retaining grooves. It is, therefore, but the work of an instant to replace a screen equipped with this device, whereas heretofore many hours of labor have often been necessary to accomplish the replacement.

In Figs. 8 and 9 there has been illustrated a modified form of the invention for use particularly with screens whose edges are retained in grooves 35 formed between a pair of vertical supporting or frame members 36 at the sides of a window or other opening. Such members 36 are frequently of wood, and in these cases the guiding members for replacing the screen when it has become disengaged may be formed easily and economically by driving staples 37 into the members 36, as illustrated clearly in Figs. 8 and 9. The staples 37 may then be bent slightly outwardly away from each other as shown in Fig. 9. The action of these guiding members 37 in replacing a screen is substantially the same as the action of the members 31 heretofore mentioned, and it is thought that further description of this form of the invention is unnecessary.

In Figs. 10 and 11, there is shown still another modification of the invention, in which the guiding member may be formed integrally on the clamping plate instead of being attached thereto as in the construction first shown. Figure 10 is a fragmentary elevation of a clamping plate 40, the edge of which has an extension or lug 41 formed thereon, and the bead 42 on the clamping plate is extended along the edge of this lug 41 as clearly shown. Fig. 11 is a cross section through a pair of clamping plates of the form shown in Fig. 10, and illustrates the fact that these lugs or extensions 41 may be bent outwardly slightly so as to diverge in the same manner.

as the loop-like guiding members 31 in the form of invention first described.

Each of the three forms of the invention heretofore disclosed acts in substantially the same way, and each comprises guiding members extending outwardly from the screen-retaining grooves so as to narrow the clear distance between the two grooves. Thus each guiding member acts in effect as an extension on the wall of the groove, and extends in a general direction toward the other groove at the opposite side of the window.

While certain preferred embodiments of the invention have been disclosed, it is to be understood that the inventive idea may be carried out in a number of ways. This application is therefore not to be limited to the precise details shown, but is intended to cover all variations and modifications thereof falling within the spirit of the invention or the scope of the appended claims.

I claim as my invention:

1. In a construction including supporting means provided with a groove, and a rolling screen having an edge normally engaged in said groove, the combination with said groove of guiding members extending from the sides of said groove toward the central portion of said screen to assist in replacing the edge of the screen which has become disengaged from the groove.

2. In a construction including supporting means provided with a groove, and a rolling screen having an edge normally engaged in said groove, the combination with said groove of guiding members extending obliquely outwardly from the sides of said groove to assist in replacing the edge of the screen which has become disengaged from the groove.

3. In a construction including supporting means provided with a groove, and a rolling screen having an edge normally engaged in said groove, the combination with said groove of means at one point for narrowing the clear distance between said groove and the center of the screen to assist in replacing the edge of a screen which has become disengaged from the groove.

4. In a construction including supporting means provided with a groove, and a rolling screen having an edge normally engaged in said groove, the combination with said groove of guiding members extending from the sides of said groove toward the central portion of said screen, said guiding members comprising loop-like elements fixed at their ends to the walls of said groove and having their mid portions spaced from the walls of said groove, said guiding members assisting in replacing the edge of a screen which has become disengaged from the groove.

5. In a construction including supporting means provided with a pair of channels substantially parallel to and spaced from each other, a rolling screen having two opposite

edges normally engaged in and longitudinally movable along said channels, and a pair of clamping plates in one of said channels, said clamping plates being on opposite sides of the screen and receiving the screen normally between them, the combination with said clamping plates of a guiding member attached to each of said clamping plates, each guiding member extending outwardly away from its associated channel and obliquely thereto, said guiding members acting, when said screen is moved longitudinally, to replace the edge of the screen which has become disengaged from the channel in which the clamping plates are disposed.

6. In a construction including supporting means provided with a pair of channels substantially parallel to and spaced from each other, a rolling screen having two opposite edges normally engaged in and longitudinally movable along said channels, and a pair of clamping plates in one of said channels, said clamping plates being on opposite sides of the screen and receiving one edge of the screen normally between them, each of said clamping plates having a beaded edge, the combination with said clamping plates of a guiding member fixed in said beaded edge of each clamping plate, each guiding member extending outwardly away from its associated channel and generally toward the other channel, said guiding members acting, when said screen is moved longitudinally, to replace the edge of a screen which has become disengaged from the channel having the clamping plates within.

7. In a construction including supporting means provided with a pair of grooves substantially parallel to and spaced from each other, a rolling screen having two opposite edges normally engaged in and longitudinally movable along said grooves, and a hollow bead at the edge of a side wall of one groove, the combination with said bead of a guiding member attached to said bead, said guiding member comprising a loop-like element having its ends fixed in said hollow bead, the mid portion of said element being spaced from the walls of said groove and extending outwardly from said groove in a general direction toward the other groove, said guiding member acting, when said screen is moved longitudinally past said member, to replace the edge of a screen which has become disengaged from the groove adjacent to which said bead is disposed.

8. The combination with a flexible and bodily movable screen, of spaced members forming guide means for an edge of said screen, and devices between the ends of said members disposed inwardly of the guiding portions thereof to return the edge of the screen which has been displaced with respect to said guiding portions to normal position

relative thereto upon longitudinal movement of the screen.

9. In a roll closure for windows comprising a guide member with a slot normally holding the edge of the rolled closure member, reseating means for said edge when it becomes displaced, said means comprising members projecting from the guide adjacent the slot thereof, the slot continuing of normal width past said projections.

10. In a roll closure comprising a guide with a slot which holds the edge of the rolled closure member when in operative position, a pair of reseating projections located adjacent said slot in said guide and near the top of said guide said slot continuing of normal width past said projections.

11. A guide for roll closures comprising portions defining a channel and a slot of substantially constant width and external protuberances of smooth form adjacent said slot.

12. A reseating guide for roll closures comprising a channel having a slot of substantially constant width and members externally projecting from the walls of said guide adjacent said slot, said members lying outside the normal path of movement of sliding members within said channel and slot.

13. In a device of the character described, having a roller, and a screen mounted on said roller to wind upon and unwind from the same, a guide associated with said roller embodying a groove normally embracing an edge of the screen but permitting longitudinal movement of the latter therein, and guiding members at the sides of the groove extending outwardly therefrom toward the center of the screen and acting to replace the edge of the screen when it becomes disengaged from the groove upon rolling the screen on said roller and thereby moving said edge longitudinally past the guiding members.

14. In a device of the character described, having a roller, and a screen mounted on said roller to wind upon and unwind from the same, a guide associated with said roller embodying a groove normally embracing an edge of the screen but permitting longitudinal movement of the latter therein, a pair of plates mounted in the groove on opposite sides of the screen to normally receive the screen between them, and a guiding member attached to each of said plates and extending outwardly away from the groove and obliquely toward the center of the screen, said guiding members acting when said screen is moved longitudinally to replace the edge thereof when it becomes disengaged from the groove.

15. In a device of the character described, having a roller, and a screen mounted on said roller to wind upon and unwind from the same, a guide associated with said roller embodying a groove normally embracing an edge of the screen but permitting longitudinal movement of the latter therein, a pair of

plates mounted in the groove on opposite sides of the screen to normally receive the screen between them, each of said plates having a beaded edge, and a guiding member fixed in the beaded edge of each plate and extending outwardly away from the groove and generally toward the center of the screen, said guiding members acting, when said screen is moved longitudinally, to replace the edge thereof should it become disengaged from the groove.
